UNITED STATES PATENT OFFICE

GEORGE ALLMAN AND STANLEY BAIRD HEMMING, OF PARKERVILLE, WESTERN
AUSTRALIA, AUSTRALIA

BROODER

Application filed August 10, 1927. Serial No. 212,060.

This invention provides an efficient and reliable brooder for the rearing of chickens, ducklings and other newly hatched birds, and which being made chiefly of metal, is easily maintained in a clean condition and free from vermin while owing to its being of a circular shape or plan is enabled to snugly accommodate a maximum number of birds. A chief structural feature of the invention resides in the means employed for the conveyance and utilization of the heat which is generated by a heater and burner which also acts as the base for the brooder.

The construction and use of the invention will be explained with the aid of the attached drawings wherein Fig. 1 is a sectional elevation showing the brooder and Fig. 2 is a vertical section of the cistern and burner.

Referring to said drawings, the brooder proper comprises a preferably circular cone shaped canopy 3, to which is secured an inner concentric conical chamber 4 by means of the chimney 5 and perforated ring flange 6. The chimney 5 is provided with a cap 7 whose duty is to prevent any foreign matter from entering same, said chimney having ports 8 for the escape of excess hot air. A sleeve 9 telescopically fits within the chimney 5 and depends a suitable depth into the chamber 4, by means of which sleeve the excess hot air is led to the outlet ports 8 aforesaid.

In said views the single and double headed arrows, respectively, denote the direction of travel of the air and heat. A space is formed between said canopy 3 and chamber 4 and acts as a hot air passage leading to the interior of the brooder proper. Within this inner chamber 4 is positioned a circular disk or baffle plate 10 lined with a sheet *a* of asbestos or other heat resisting material, said plate being spaced above the floor of the chamber 4 and above the upper end 11 of the chimney 12 of the burner. The purpose of this plate 10 is to deflect the heat on to the floor of said chamber 4. Concentric with the chimney 12 and depending from the underside of the chamber is a cylindrical tube 13 which terminates at a point above the floor or support for the brooder. The purpose of this tube 13 is to guide the fresh air to the burner. An

outer tubular member 14 concentric with the tube 13 depends from the bottom of the chamber 4 and has its lower edge seated on the oil cistern 15 of the burner. The upper portion of said tubular member 14 is perforated at 16 to allow of the admission of air to the burner through the perforated lower end 17 of the burner chimney 12. Depending from the outer edge of the canopy 3 is a curtain 18 having openings 19 for the admission of fresh air and also for the passage of the birds. Said curtain at its upper edge is secured by a circumferential clamping ring 20 or in any desired manner to the canopy aforesaid. The oil cistern 15 for the burner is preferably circular in shape and in use is buried slightly below ground level as shown in Fig. 2, so that its top is flush with said level and forms the floor of the brooder. This cistern is made with an upstanding circular flange 21 which acts as a guard for the birds within the brooder, and said flange telescopes neatly with the dependent tubular member 14 aforesaid.

The cistern is provided with a sealing plug 22 adapted to interscrew with a flange 23 fitted in the top opening of the oil cistern 15 and, said plug when removed permits of the filling and emptying of the cistern.

The plug 22 is made with a central opening 24 for the reception of the wick tube 24 having openings 25 adjacent its lower end for the admission of the feed oil to the wick. This sealing plug 22 is made with a flange 26 to provide means for regulating the flame by screwing and unscrewing said plug 22. The wick tube 24 is provided at its lower end with a seating member 27 to rest upon the bottom of the cistern and maintain said tube in an upright position when the plug 22 is removed. The operation of the brooder is as follows: When the wick in the tube 24 is ignited air is drawn from the outer atmosphere through the openings 19 of the curtain 18, and passes through the perforated upper end 16 of the tubular member 14 and traveling downwardly between the tube 13 and tubular member 14 enters through the open perforations 17 of the chimney 12 to flame.

The now heated air rises through said

chimney 12 and is radially diverted or spread between the baffle plate 10 and the bottom of the chamber 4 into the chamber 4 during which the heat downwardly radiates through the floor of said chamber into the brooder compartment.

The heat also radiates through the sloping walls of the chamber 4 into the concentric passage between said chamber and the canopy 3 from whence it passes downwardly between the outer edge of the chamber 4 and curtain 18 into the brooder compartment. The perforations of the ring flange 6 allow free passing of the heat through said passage. The 15 excess hot air from the chamber 4 travels up through sleeve 9 and out of the chimney 5.

What we claim as our invention and desire to secure by Letters Patent is:

1. A brooder comprising a canopy having a central opening, a chamber below said canopy, said chamber having an upper wall parallel to but spaced from the under side of said canopy and a lower wall, the upper and lower walls of said chamber having apertures in vertical alignment with the opening in the canopy, a chimney extending from the opening in the upper wall of said chamber through the opening in the canopy, a tube depending from the opening in the lower wall of the chamber, a baffle in said chamber above the opening in the lower wall thereof and spaced from said wall, and a sleeve telescopically adjustable in said chimney to vary the space between its lower end and said upper side of said baffle.

2. A brooder according to claim 1 wherein the canopy and the upper wall of the chamber are of substantially cone-shape.

3. A brooder according to claim 1 embodying a burner below the lower end of the tube and a burner chimney within and spaced from said tube and surrounding said burner, said burner chimney having its lower portion extending below the lower end of said tube and provided with perforations.

4. A brooder according to claim 1 embodying a burner below the lower end of the tube, a burner chimney surrounding the burner and spaced from said tube, said burner chimney having its lower portion extending below the lower end of said tube and having perforations in its lower portion, and a tubular member depending from the lower wall of the chamber and surrounding but spaced from the tube, said tubular member having its lower end extending below the lower end of the tube and being perforated adjacent its upper end.

5. A brooder according to claim 1, including an oil cistern having a filling opening in its top and a flange concentric with said opening and extending upwardly from said cistern, a tubular member depending from the underside of the chamber in telescopic relation with said flange and surrounding the

tube, said tubular member having air admission openings adjacent its upper end, a sealing plug for said filling opening, a wick tube vertically movable through said plug and having a seating member at its lower end, and 70 a chimney within the tube and surrounding said wick tube.

In testimony whereof we have hereunto set our hands.

GEORGE ALLMAN.

STANLEY BAIRD HEMMING.
